Raymond I. Martin, 202 Bertrand Road, Niles, Mich.

Filed Nov. 23, 1959, Ser. No. 58,440

Term of patent 14 years

(Cl. D52—6)

FIG. 1 is a face view of a drawing template showing my new design;

FIG. 2 is an edge view thereof;

FIG. 3 is a fragmentary enlarged sectional view taken on line 3—3 of FIG. 1;

FIG. 4 is a fragmentary enlarged sectional view taken on line 4—4 of FIG. 1;

FIG. 5 is a fragmentary enlarged sectional view taken on line 5—5 of FIG. 1;

FIG. 6 is a fragmentary enlarged sectional view taken on line 6—6 of FIG. 1.

The bottom side of the template is plain and substantially like the top or face view, except that the beveled edges of the openings are not visible therat.

The characteristic features of the design for the template disclosed reside in the symbols and their particular arrangement shown.

I claim:

The ornamental design for a drawing template, as shown and described.
